UNITED STATES PATENT OFFICE.

HARRY E. RUTTLE, OF CHICAGO, ILLINOIS.

GLOBE HOLDER.

Application filed February 20, 1922. Serial No. 537,750.

To all whom it may concern:

Be it known that I, HARRY E. RUTTLE, a citizen of the United States of America, and a resident of Chicago, county of Cook, and 5 State of Illinois, have invented a new and useful Improvement in Globe Holders, of which the following is a specification.

This invention relates to lighting fixtures and especially to means for detachably 10 securing globes, shades and the like, as for instance in connection with electric lighting systems.

Heretofore it has been customary to provide shade and globe holders with a flange 15 of substantially cylindrical shape or the equivalent thereof provided with three radially disposed inwardly pointing screws to engage the neck or flanged inner edge of the shade or globe. It has been found that in 20 the use of such devices as ordinarily applied in connection with the larger sizes of globes and particularly in outside service as in street lighting, there is great wastage on account of breakage resulting from improper 25 setting of the screws and from relative expansion and contraction of the interlocked members due to variations in temperature whereby the globes are cracked and ultimately broken. Moreover, such use of 30 screws for holding globes is found to be wasteful of time and labor in connection with maintenance, as the globes have to be removed occasionally for cleaning and for renewal of the lamps, and the turning and 35 adjustment of a plurality of screws takes a considerable amount of attention.

The main objects of this invention are to provide an improved form of globe holder adapted to facilitate and expedite access to 40 the lamps and interchange of globes, and more particularly to provide an improved form of fastening mechanism adapted to grip the globe somewhat yieldingly and adapted for ready operation to engage or 45 release the globe. A further object is to provide such a fastening of simple and inexpensive construction, adapted for application to standard globe holder frames already in use and also adapted for gripping and releasing the globe by a single manual operation as, for instance, the turning of a single screw.

An illustrative embodiment of this invention is shown in the accompanying drawings, in which—

Figure 1 is a vertical axial section of a

globe holder and globe mounted dependingly and showing the lamp in dotted lines.

Figure 2 is a section on the line 2--2 of Figure 1.

Figure 3 is an enlarged view of the manual clamp mainly in axial section on the line 3--3 of Figure 1.

In the construction shown in the drawings the globe 1 is held in place by the combined 65 lamp socket housing and holder 2, comprising mainly a rigid annular frame or body part 3, a resilient manually operable arcuate globe clamping part 4 secured to the part 3 in a manner hereinafter described and a 70 stationarily mounted arcuate globe engaging part 5 somewhat similar in shape to the part 4 and disposed oppositely thereto. The members 4 and 5 mutually embrace the neck 75 1' of the globe and extend nearly around the same, as shown in Fig. 2.

The holder 2 is secured rigidly to its support 6 by means of bolts, screws or the like 7 in the flat base part 3'. Although a depending arrangement of the globe is here 80 shown as required for instance in ceiling work, it is to be understood that the holder may equally well be mounted uprightly on the top of a post, not shown, as frequently required for street lighting, in which case the 85 hole 3'' provides for draining off any moisture tending to collect in frame 3. The support 6 is apertured or hollow as shown at 6' to accommodate the current supply wires, not shown.

One of the complementary bow-shaped embracing members, namely the stationary bar 5 is in the form of a somewhat yielding wire having its ends looped and secured to the inner side of the flange or frame 3 where 95 they are held by screws or bolts 8. One end of member 5 adjacent to the free end of member 4 extends appreciably past the adjacent bolt 8 and is looped back at 9 as shown in Figure 2.

The manually adjustable embracing member 4 has one end secured substantially rigidly by the bolt 8 which holds the corresponding end of bar 5. The opposite or free end of member 4 is provided with a fastening in the form of a thumb screw 10 adapted for securing same releasably against the outer side of the flange or frame 3 as clearly shown at the right on Figures 1 and 2. Said member 4 extends considerably past the 105 screw 10 toward the loop 9 of bar 5 and is looped back at 11. The extremity of the

free end of member 4 is inclined outwardly somewhat across the edge of said flange as shown at 12 and downwardly where its tip 13 is looped to receive the shank of a hollow screw-bolt 14 which is provided with a nut 15 as shown in Figure 3. The screw 10 has a knurled head 10' and a shank 10'' threaded to fit the correspondingly threaded bolt 14 and also the threaded hole 16 in the flange of frame 3.

The operation for installing a globe is as follows: The screw 10 is backed out of engagement with frame 3 and permitted to spring outwardly so as to admit the flanged neck 1' of the globe 1 which fits snugly against the member 5. The member 4 is then sprung forcibly inwardly to clamp against the opposite side of the globe neck and so as to bring the screw 10 into registry with the aperture 16. Said screw is then given a few turns in the forward direction so as to lock spring 4 in place. Loss of the screw 10 is prevented by the permanent threaded engagement of said screw with the 25 terminal piece 14 on spring clamp 4.

In order to remove the globe as for cleaning or renewal the operation is reversed. The shape of the globe or shade is immaterial so long as it has a neck part such as 1' or the equivalent. When the clamp is set in place the resilience of the wires 4 and 5 provide for sufficient play to prevent breakage under the stresses generated by changes in temperature. Moreover the globe is cushioned against destructive jarring such as may occur in buildings or elsewhere. In use the device is a great convenience and time saver, for while the globe may be set in place with one hand the locking arm 4 may be operated and set by a simple turning of screw 10 with the other hand.

Although but one specific embodiment of this invention has been herein shown and

described, it will be understood that numerous details of the construction shown may be altered or omitted without departing from the spirit of this invention as defined by the following claims.

I claim:

1. A holder of the character described comprising an annular frame having a flange with three mutually spaced and radially disposed threaded apertures therein, screws for two of said apertures, a wire disposed arcuately between two of said apertures and secured by the screws therein, and a complementary wire disposed similarly on the opposite side of said frame and provided with a thumb screw carried thereby adapted and arranged for convenient attachment and release of said end by engagement with the third aperture.

2. A holder of the character described comprising a rigid frame of annular shape in combination with a resilient clamping member of arcuate shape having one end secured substantially permanently and rigidly to said frame and the other end being provided with radially disposed screw means secured releasably.

3. A globe holder having an arcuate resilient clamping member formed and adapted to engage the neck of the globe, one end of which member is permanently secured in a fixed position and the other end being provided with a radially threaded terminal, in combination with a thumb screw adapted and arranged to releasably secure the corresponding end of said member, the said other end also being bent back outwardly in the plane of said member and arranged to provide a yielding spring pressure against the globe neck.

Signed at Chicago this 18 day of Feb. 85 1922.

HARRY E. RUTTLE.
